UNITED STATES PATENT OFFICE

99,276

DESIGN FOR A VENDING CABINET

Edwin R. Fuller, Los Angeles, Calif.

Application February 24, 1936, Serial No. 61,326

Term of patent 3½ years

To all whom it may concern:

Be it known that I, Edwin R. Fuller, a citizen of the United States, residing at Los Angeles, in the county of Los Angeles and State of California, have invented a new, original, and ornamental Design for a Vending Cabinet, of which the following is a specification, reference being had to the accompanying drawing forming part thereof.

Figure 1 is a perspective view of my vending cabinet illustrating mainly the front, one side, and a portion of the top, and may be considered

as taken approximately in the direction of the arrows 1 of Figures 2 and 3;

Figure 2 is a side elevation taken in the direction of the arrow 2 of Figure 3; and

Figure 3 is a plan taken in the direction of the arrow 3 of Figures 1 and 2.

I claim:

The ornamental design for a vending cabinet as shown.

EDWIN R. FULLER.
